US00D894272S

(12) **United States Design Patent** (10) **Patent No.:** **US D894,272 S**
(45) **Date of Patent:** **** Aug. 25, 2020**

(54) **FRONT PANEL OF MULTI-FUNCTION ELECTROPHOTOGRAPHIC PRINTER SCANNER**

(71) Applicant: **Lexmark International, Inc.**, Lexington, KY (US)

(72) Inventors: **Darin Michael Gettelfinger**, Lexington, KY (US); **Matthew Ryan Keniston**, Lexington, KY (US); **Franklin Joseph Palumbo**, Nicholasville, KY (US); **Michael James Shanor**, Lexington, KY (US); **Jay Scott Siekmann**, Nicholasville, KY (US); **Christopher Kent Washing**, Lexington, KY (US)

(73) Assignee: **LEXMARK INTERNATIONAL, INC.**, Lexington, KY (US)

(**) Term: **15 Years**

(21) Appl. No.: **29/655,633**

(22) Filed: **Jul. 5, 2018**

Related U.S. Application Data

(63) Continuation of application No. 29/547,833, filed on Dec. 8, 2015, now abandoned.

Primary Examiner — Lauren D McVey

(57) **CLAIM**

The ornamental design for a front panel of multi-function electrophotographic printer scanner, as shown and described.

DESCRIPTION

FIG. 1 is a front, top, and right side perspective view of a front panel of a multi-function electrophotographic printer scanner showing our new design;

FIG. 2 is a rear, top, and left side perspective thereof;

FIG. 3 is a front elevation thereof;

FIG. 4 is a right side view elevation thereof;

FIG. 5 is a rear elevation view thereof;

FIG. 6 is a left side elevation view thereof; and,

FIG. 7 is a top plan view thereof.

The bottom of the multi-function electrophotographic printer scanner is not shown and is not claimed.

(Continued)

The features shown in broken lines depict environmental subject matter only and form no part of the claimed design.

1 Claim, 7 Drawing Sheets
